UNITED STATES PATENT OFFICE

ELMER A. SMITH, OF FLINT, MICHIGAN

INTERNAL COMBUSTION ENGINE

Application filed September 17, 1931. Serial No. 563,393.

This invention relates to an internal combustion engine and it aims to provide a double construction having free and unobstructed combustion chambers on both sides of the piston head.

It is generally aimed to secure light weight power and speed without sacrifice of material and such a construction as may be built for operation on the four stroke cycle, eight stroke cycle or otherwise. The engine, in the case of a four stroke cycle serves to increase the power per poundage approximately one hundred per centum compared to the average engine of similar cycle construction.

The more specific objects and advantages will become apparent from a consideration of the description following taken in connection with accompanying drawings illustrating an operative embodiment.

In said drawings:—

Figure 1 is a view in central vertical sectional view through a cylinder of the improved engine.

Figure 2 is a cross sectional view taken on the line 2—2 of Figure 1.

Figure 3 is a cross sectional view taken on the line 3—3 of Figure 1.

Figure 4 is a vertical sectional view taken at a right angle to Figure 1.

Figure 5 is a side elevation of the piston alone,

Figure 6 is a side elevation of the anvil alone, and

Figure 7 is an inverted plan view of the cylinder alone.

Referring specifically to the drawings, 10 designates a crank case, to which a cylinder generally designated 11 is bolted or otherwise fastened as at 12. Said cylinder has diametrically opposite enlargements 13, affording guide channels 14.

Vertically reciprocable within the cylinder 11, is a piston generally designated 15 which is detailed in Figure 5. Said piston is closed at the top by wall 16, and peripherally thereof has suitable rings or packings 17 in engagement with the inner wall of the cylinder 11. In addition, said piston 15 has hollow projections at 18, which are adapted to travel in the guide ways 14.

An anvil or fixed abutment generally designated 19, has a closed head 20 at the top and adjacent the periphery thereof is provided with rings or packing 21 which engages the inner wall of piston 15.

The crank shaft of the engine is suggested at 22 and a connecting rod 23 extends therefrom and is connected to a wrist pin 24, which is secured to the piston in the sleeve or projection 18 thereof, suitable fastenings preferably being used as at 24' to hold the wrist pin in place. It will be noted that the anvil has vertical elongated slots 25 at the sides thereof of accommodating movement of the wrist pin 24.

It will further be noted that the lower end of the piston 15 is divided or split so as to provide skirt portions 26, which are received in and guided by arcuate slots 27 provided in the lower end of the anvil. Said anvil has a base flange 28, which is secured in place by the bolts 12 and also has ports or openings 29, in registry with the guide ways 14.

The explosions take place between the head of anvil 20 and the head 16 of piston 15, also between the cylinder head and the piston head. The intake of fuel, and exhaustion of spent fuel for the chamber 30 inside of piston 15 takes place through suitable ports 31 in the piston 15 coacting with a port 32, port 33 being provided for intake and exhaust in chamber 34 between piston 15 and cylinder head 35. The ignition system, crank case, valve mechanism and in fact all exterior parts form no part of the invention and hence have not been shown or at least have been shown but conventionally. Also the cylinder may be water-jacketed, as shown, or air-cooled. The engine may be built in any of the approved types, that is cylinders in line, X type, W type, V type, radial or opposed, using any kind of approved valve, cam or crank arrangement.

The ignition of the compressed charge in the chambers 30 and 34 may be effected by means of spark plugs or other ignition devices that may be placed in the valve chambers (not shown), or other selected location.

It will be noted that the ports 29 permit lubricant to enter the guide ways 14.

Various changes may be resorted to provided they fall within the spirit and scope of the invention.

I claim as my invention:—

- 5 1. An engine of the class described comprising a cylinder, a piston operable in said cylinder, a fixed anvil, a combustion chamber provided between the cylinder and said anvil, a wrist pin for the cylinder, said anvil 10 having vertical slots through which the wrist pin moves, said cylinder providing guide ways for movement of the opposite ends of the wrist pin, said anvil having an outwardly extending flange disposed under the cylinder and having ports in registry with said 15 passageway.
2. An engine of the class described comprising a cylinder, a piston operable in said cylinder, a fixed anvil, a combustion chamber 20 provided between the cylinder and said anvil, a wrist pin for the cylinder, said anvil having vertical slots through which the wrist pin moves, said cylinder providing guide ways for movement of the opposite ends of the 25 wrist pin, said anvil having an outwardly extending flange disposed under the cylinder and having ports in registry with said passageway, said flange having arcuate slots therethrough, and said cylinder having divided portions disposed and movable in said 30 arcuate slots.
3. An engine of the class described comprising in combination with a crank case, a cylinder, said cylinder having diametrically 35 offset portions affording guide ways, a hollow piston operable in said cylinder, an anvil located within the piston, said anvil having an outwardly extending flange disposed between the base of the cylinder and said crank 40 case, hollow projections on the piston disposed in said guide ways, said flange having ports in registry with the guide ways and having arcuate slots, said piston having spaced skirt portions disposed and movable 45 in said slots, a wrist pin on the piston extending into said projections, a connecting rod engaging the wrist pin and adapted for coaction with the crank shaft of the engine, and said anvil having vertical slots through 50 which the wrist pin moves.

In testimony whereof I affix my signature.

ELMER A. SMITH.
